Patented Nov. 5, 1963

196,820

PHOTOGRAPHIC ENLARGER

Julius Durst, Bressanone, near Bolzano, Bolzano, Italy,
assignor to Durst S.p.A. Fabrica Macchine ed Appa-
recchi Fototechnici, Bolzano, Italy

Filed July 20, 1962, Ser. No. 70,999

Term of patent 14 years

Claims priority, application Italy Mar. 27, 1962

(Cl. D61—1)

Fig.1.

Des. 196,820

PAGE 2

Fig. 2.

Fig. 3.

FIG. 1 is a side perspective view of a photographic enlarger showing my new design, the side opposite thereto being similar in appearance except for the omission of the control knobs;

FIG. 2 is a front perspective view thereof with portions of the base being shown broken away for convenience of illustration; and

FIG. 3 is a top plan view thereof.

I claim:

The ornamental design for a photographic enlarger, as shown and described.
